UNITED STATES PATENT OFFICE

PAUL F. WILLIAMS, OF CHICAGO, ILLINOIS, ASSIGNOR TO G. & W. ELECTRIC SPECIALTY CO., OF CHICAGO, ILLINOIS, A CORPORATION OF ILLINOIS

CONDUCTOR DISCONNECTER

Application filed May 20, 1925. Serial No. 31,533.

This invention relates to a device for connecting and disconnecting electrical conductors.

One object of the invention is to provide 5 simple, reliable and efficient means for electrically connecting and disconnecting electrical conductors in a manner insuring an intimate electrical contact between conductors and which permits of ready disconnection of 10 said conductors.

Another object is to provide an electrical 15 disconnecter for electrical conductors of the pothead type, in which the parts cooperate in a new and improved manner to produce efficient results, and whereby burning of the main contacts is avoided.

Another object is to provide a device of the 20 class described adapted to meet all of the requirements under service conditions.

These and other objects are accomplished by means of the arrangement disclosed on the accompanying sheet of drawings, in which

Fig. 1 is a vertical longitudinal sectional 25 view of a conductor disconnector of the pothead type embodying my invention;

Fig. 2 is a transverse sectional view taken in the plane of line 2--2 of Fig. 1; and

Fig. 3 is a detail elevational view showing 30 the band and its operating mechanism, whereby the contact cylinders are pressed into engagement with each other for making an intimate electrical contact therebetween.

The various novel features of the invention 35 will be apparent from the following description and drawings and will be particularly pointed out in the appended claims.

Referring to the figures of the drawings, 40 it will be noted that my invention is illustrated in connection with a disconnector of the pothead type, in which the body 10 of the pothead receives one connector member 11 and the cap 12 receives another connector member 13. The connector 11 is secured in 45 position between shoulders 14 and 15 in the body of the pothead by means including a collar portion 16 at one end of the connector 11 and nuts 17 threaded onto the other end of said connector. A ground cable 18 is shown 50 electrically connected to the connector 11 in

the usual way, at 19, said cable 18 being otherwise sealed to the body portion 10 in the usual manner.

An overhead or other cable 20, entering the cap and properly sealed thereto, is electrically connected in the usual manner at 21 to the connector 13. A supporting collar 22 is cemented in position in the cap 12 and has a shoulder 23 upon which the connector 13 rests, there being a nut 24 engaging the opposite end of said collar 22 for clamping the connector 13 in position. The connector 13 terminates in a yieldably split plug 25 which is received by a socket portion 26 formed in the upper end of connector 11. Accordingly 55 it will be appreciated that when the cap 12 is placed down over the body 10 in its normal position, an electrical connection will be made between the cables 18 and 20 by virtue of the plug and socket members 25 and 26. 60 Such electrical connection, however, does not form the main electrical connection between the cables 18 and 20, but is of an auxiliary 65 nature. It will be noted that a contact cylinder 27, having an upper flange 28, is electrically connected and clamped to a collar 29 on the connector 11 by a nut 30 threaded onto the upper end of the connector 11. Similarly, a contact cylinder 31, having a flange 32, is electrically connected to the other connector 13 and is clamped between the nut 24 and another nut 33 threaded onto the connector 13. The outer contact cylinder 31 has 70 a plurality of circumferentially spaced flexible tongues 34 which are telescopically arranged with respect to the inner contact cylinder 27. As shown in Fig. 1, the flexible 75 tongues 34 are in electrical engagement with the inner contact cylinder 27, but means are provided for making said electrical connection 80 more intimate for forming the main electrical connection between the cables 18 and 20. Said means take the form of a flexible band 35, which surrounds or embraces 85 the outer contact cylinder 31 and its tongues 34 and is adapted, when properly actuated, to press the spring contact fingers 36 radially or laterally inwardly into a more intimate 90 engagement with the inner contact cylinder 27 for improving the electrical connection. 95

100

The band may be supported on the outer contact cylinder, and more particularly by an annular flange 36^a formed at the lower ends of the flexible tongues 34 thereof. The free ends of the band are secured to an actuating member whereby the band may be applied for making the intimate electrical contact or may be released preparatory to an electrical disconnection. This actuating member takes the form of a rod 36 having an operating handle 36' and also having portions 37 and 38 which are eccentric with respect to another portion 39. One end of the band 35 has a plurality of looped portions 40 which are secured to the rod portions 37 and 38, and the other end of the band has one or more loop portions, only one 41 being shown, looped around and secured to the rod portion 39.

As shown particularly in Fig. 1, the band 35 is loose and the portions 37, 38 and 39, which are eccentric with respect to each other, have such eccentric portions in radial alignment. If the rod 36 is now rotated upon its axis in one direction, it will be appreciated that the portions 37 and 38, which are eccentric with respect to the rod portions 39, will move out of their radial relationship for clamping the band 35 against the flexible tongues 34 of the outer contact cylinder for forcing said flexible tongues into more intimate engagement with the inner contact cylinder 27 for making a more intimate electrical connection between the cables 18 and 20.

If for any reason it is desired to electrically disconnect the cables 18 and 20, the control rod 36 is rotated in the opposite direction so that the eccentric portions 37, 38 and 39 become radially aligned for loosening the band 35 for making the electrical engagement between the inner contact cylinder 27 and the flexible tongues 34 of the outer contact cylinder 31 less intimate, whereupon the pothead cap may be pulled away from the pothead body 10, which results in electrical disconnection between the connectors 11 and 13, connected respectively to the cables 18 and 20. Attention is called to the fact that the flexible plug 25 of connector 13 remains in electrical engagement with the socket portion 26 of connector 11 longer than the outer contact cylinder remains in electrical engagement with the inner contact cylinder 27 by virtue of the fact that the interengaging portions of the plug 25 and socket 26 are greater in length than the corresponding interengaging portions of the inner and outer contact cylinders 27 and 31. As a result thereof, the circuit of the cables 18 and 20 is finally broken between the contact plug 25 and the socket portion 26 of the connectors 13 and 11 respectively. In other words, it might be said that such portions comprise the arcing tips for protecting the main contacts, which are the contact cylinders 31 and 27.

By means of this combination, electrical

connection between the two cables may be quickly made and broken, the connections, when made, being intimate and efficient, the main contacts being protected against any injury resulting from arcing.

I claim:

1. In a device of the class described, a cable, a contact cylinder electrically connected thereto, another cable, a contact cylinder electrically connected to said second cable and having a yieldable portion telescopically arranged with respect to the first contact cylinder, and flexible means for pressing the yieldable portion of said second contact cylinder into engagement with said first contact cylinder for making an intimate electrical contact therebetween, and means associated with said flexible means and operable to selectively release intimate contact between said cylinders.

2. In a device of the class described, the combination of a cable, a contact cylinder electrically connected thereto, another cable, a contact cylinder electrically connected to said second cable, said contact cylinders being telescopically arranged, and flexible means for pressing one of said cylinders into intimate engagement with said other cylinder for making an intimate electrical contact therebetween, and means associated with said flexible means and operable to selectively release intimate contact between said cylinders.

3. In a device of the class described, the combination of a plurality of electrical conductors, a contact cylinder electrically connected to each of said conductors and being telescopically arranged, and flexible means for pressing one of said contact cylinders laterally into more intimate engagement with respect to the other cylinder for improving the electrical connection, and means associated with said flexible means and operable to selectively release intimate contact between said cylinders.

4. In a device of the class described, the combination of a plurality of electrical conductors, a contact member electrically connected to each of said conductors, one of said contact members being flexible, and flexible means embracing said contact members for pressing said flexible contact member into engagement with the other contact member for making a more intimate electrical connection between said contact members, and means associated with said flexible means and operable to selectively release intimate contact between said contact members.

5. In a device of the class described, the combination of a plurality of electrical conductors, a contact member electrically connected to each of said conductors, and a flexible band for pressing one of said contact members into intimate engagement with the other contact member for improving the elec-

trical connection, said band having a member secured thereto and operable to selectively release the improved connection between said contact members.

5 6. In a device of the class described, the combination of a plurality of electrical conductors, a contact cylinder electrically connected to each of said conductors and being telescopically arranged, one of said contact cylinders having flexible tongues adapted to engage the other contact cylinder, and flexible means for pressing said tongues into intimate engagement with said other contact cylinder for improving the electrical connection therebetween, said means having a member secured thereto and operable to selectively release the improved connection between said contact cylinder and tongues.

10 7. In a device of the class described, the combination of a plurality of electrical conductors, a contact cylinder electrically connected to each of said conductors and being telescopically arranged, one of said contact cylinders having flexible tongues adapted to engage the other contact cylinder, and a flexible band for pressing said tongues into intimate engagement with said other contact cylinder for improving the electrical connections therebetween, said band having a member secured thereto and operable to selectively release the improved connection between said contact cylinder and tongues.

15 8. In a device of the class described, the combination of a plurality of electrical conductors, a contact cylinder electrically connected to each of said conductors and being telescopically arranged, a band embracing said contact cylinders, and means hinged to said band for controlling the tightness of said band for controlling the intimacy of the electrical engagement between said contact cylinders, said means being provided with offset portions cooperating with the band whereby movement of said means changes the position of said offset portions to control tightness of the band.

20 9. In a device of the class described, the combination of a plurality of electrical conductors, a contact cylinder electrically connected to each conductor and being telescopically arranged, one of said contact cylinders being flexible, means for pressing said flexible contact cylinder into intimate engagement with said other contact cylinder for improving the electrical connection, means for affecting the degree of engagement, and other contact members for forming another electrical connection between said conductors adapted to be disconnected after said contact cylinders are disconnected for protecting the latter against arcing.

25 10. In a device of the class described, the combination of a cable, a connector connected to said cable and having a socket portion, another cable, a connector electrically con-

nected to said second cable and having a plug portion adapted to make electrical contact with the socket portion of said other connector, contact cylinders electrically connected to each of said connectors and being telescopically arranged, and means for controlling the intimacy of the electrical contact between said contact cylinders.

70 11. In a device of the class described, the combination of a cable, a connector connected to said cable and having a socket portion, another cable, a connector electrically connected to said other cable and having a plug portion adapted to make electrical contact with the socket portion of said other connector, contact cylinders electrically connected to each of said connectors and being telescopically arranged, and a member embracing said contact cylinders for controlling the intimacy of their electrical engagement.

75 12. In a device of the class described, the combination of a cable, a connector electrically connected to said cable and having a socket portion, another cable, a connector electrically connected to said second cable and having a plug portion adapted to make electrical contact with the socket portion of said other connector, contact cylinders electrically connected to each of said connectors and being telescopically arranged, and a flexible band embracing said contact cylinders for controlling the intimacy of the electrical contact between said contact cylinders.

80 13. In a device of the character described, the combination of a supporting bushing having an enlarged downwardly opening recess, a cable entering said bushing and connected to a connector supported by said bushing and having a portion in said recess, an elongated insulating bushing having a connector therein secured to a cable, each of said connectors having a contact cylinder thereon, the contact cylinders being adapted to have telescopic relation to each other whereby the electrical connection is effected between the cables, one of said contact cylinders being flexible, supporting means on said flexible cylinder, a flexible band embracing said flexible cylinder, and means for tightening said band for releasably improving the connection between cylinders in said recess.

85 14. In a device of the character described, the combination of a supporting bushing having an enlarged downwardly opening recess, a cable entering said bushing and connected to a connector supported by said bushing and having a portion in said recess, an elongated insulating bushing having a connector therein secured to a cable, each of said connectors having a contact cylinder thereon, the contact cylinders being adapted to have interfitting relation to each other whereby electrical connection is effected between cables, one of said contact cylinders being

flexible, supporting means on said flexible cylinder, and means for releasably tightening said band, said last named means including an operating handle disposed externally of said recess and having a portion extending in said recess having offsets thereon connected to portions of said flexible band whereby movement of said handle changes the position of said offsets to releasably tighten said band.

- 10 15. In a device of the character described, the combination of a supporting bushing having an enlarged downwardly opening recess, a cable entering said bushing and connected to a connector supported by means in said bushing and having a portion in said recess, an elongated insulating bushing having a connector therein secured to a cable, said connector having a portion adapted to have electrical connection with said first named connector in said recess, and means operable by eccentric means controlled externally of said recess and cooperating with said connectors for releasably improving the connection therebetween in said recess, said means cooperating with said connectors being adapted to release electrical connection before connection is released between the connector portion and its associated connector.
